FLOOR FINISHING MACHINE

Clinton E. Woods, Philadelphia, Pa.; Julia E. Woods, administratrix of said Clinton E. Woods, deceased, assignor to Julia E. Woods individually, Yeadon, Pa.

Application May 13, 1927. Serial No. 191,008

25 Claims. (Cl. 91—39)

The object of the invention is to provide improvements in various types of surface finishing machines, but more especially in machines designed for waxing floors and similar surfaces in which finishing material of such nature is used, that it flows more freely and performs its intended function better when heated.

Another object therefore is to provide broadly in such machines various means for heating and maintaining the wax, or other material, at substantially a given predetermined temperature, to insure its flowing freely through the channels of the device before it reaches the floor, and its entering the pores of the floor surface upon striking the same, as well as insuring a better resulting polish after manipulation by the brushes of the device upon such surface.

A further object is to provide such a device, comprising a polishing member, an electric motor to drive said member, a reservoir for surface finishing material, a channel extending through or closely adjacent to said motor and adapted to be heated by the waste heat generated therein, and conveying means to lead said material from said reservoir to said channel and from said channel to said polishing member.

Still another object is to provide a form of the device in which a reservoir is carried closely adjacent to the motor and is constantly heated thereby while the latter is in operation, said reservoir, if desired, comprising an integral hollow extension of the motor frame; also, if the waste heat from the motor is not sufficient for the purpose intended, there is provided an electrically energized immersion heater unit which extends into said reservoir preferably below the normal level of the liquid therein, and is energized by electric current supplied thereto preferably in parallel with the motor, and a suitable thermostatic means to control the flow of current through said unit, irrespective of the operation of the motor.

And a still further object is to provide a form of the device wherein there is a combination of an electric motor having a shaft, a polishing member carried by a second shaft, gearing connecting said shafts, a casing surrounding said motor and said shafts and providing a chamber surrounding said gearing, and a conduit adapted to lead a liquid or semi-liquid material from a suitable reservoir and into said chamber, where said material is raised in temperature by waste heat conducted thereto by said casing from said motor, and is stirred and churned into a homogeneous mass before passing from said chamber

to be manipulated by said polishing member, said material while in said chamber also serving as a lubricant for said gearing.

With these and other objects in mind, the present invention comprises further details of construction and operation, which are fully brought out in the following description, when read in conjunction with the accompanying drawings, in which Fig. 1 is a front elevation of one embodiment of the invention showing a portion of the same in vertical section; Fig. 2 is a substantially central vertical transverse section of the same; Fig. 3 is a section on the line 3—3 of Fig. 1; Fig. 4 is a perspective view of the heating coil shown in Figs. 1 to 3 inclusive; Fig. 5 is a front elevation of a modified form of the device showing a liquid reservoir comprising an integral part of the motor and gear casing and also showing an electric immersion heater extending into said reservoir with an electrically operated thermostat adapted to regulate the flow of current through said heater; Fig. 6 is a vertical section on the line 6—6 of Fig. 5; Fig. 7 is a horizontal section on the line 7—7 of Fig. 5; Fig. 8 is a vertical section on the line 8—8 of Fig. 5; and Fig. 9 is a vertical section of a modified form of the device taken through one of the upwardly extending countershafts of the device and through a reservoir in the handle of the same.

Referring to Figs. 1 to 4 inclusive, a finishing device for hard-wood floors and similar surfaces comprises a plurality of brush or other suitable members 10, rotatable in substantially a common plane and removably mounted through the medium of any suitable hollow connection 11, upon the lower end portion of an upwardly extending shaft 12, in turn having an axial bore 13. Said shaft is rotatably supported by bail bearing 14 or the like within a casing 15, which merges upwardly into a housing 16, which housing surrounds a worm gear 17, carried by said shaft 12, while a worm 18 meshes with said gear and in turn is carried by the shaft 19 of a motor having an armature 20 rotatable within a set of field coils 21.

The field coils are mounted upon the interior of a substantially cylindrical motor casing 22, providing spaces 23, between said field coils and upon the diametrically opposite sides of the armature. In one of said spaces, particularly when said field coils lie in a horizontal plane, a suitably shaped coil of tubing, such as is shown in Fig. 4, may be positioned, or if said field coils lie in a vertical plane, the uppermost portion of the casing 22 may be cut away to provide a cavity

24, in which such a coil of tubing may be housed, the cavity in such case being normally covered by a removable plate 25 or the like.

In each case said coil comprises a series of substantially parallel sections 26, having a coupling 27 at one end by which said coil is connected through the medium of a flexible tube 28 to a channel 29 in the depending section of the central portion 30 of a yoke, having arms 31 by which it is pivotally mounted at 32 to the substantially unit casing, which includes the motor casing 22, the housing 16, and the shaft casing 15, as well as a canopy 33 and skirt 34, which together cover and substantially surround the rotary finishing member 10.

The central portion 30 of said yoke is provided with a valve 35, to control the flow of a fluid through the channel 29 from the interior of a preferably tubular handle 36, which comprises in this instance a reservoir having a diagonally upwardly extending and laterally positioned intake aperture 37, provided with a removable closure 38. However, instead of this type of reservoir, any other suitable construction may be employed, such for instance, as that of employing in inverted position a can or other container, in which the finishing fluid or wax is sold.

The opposite end portion of the coil illustrated is divided and leads into diverging channels 39 and 40, corresponding in number to the rotary finishing members 10, and terminating in downwardly extending projections 41, which pass through a suitable stuffing box 42 in a cap 43 covering the housing 16, and thence preferably through a second stuffing box 44 into the upper end of the respective bores 13 in the shafts 12. The function and operation of this series of tubing is the same, regardless of whether it is positioned in a cavity in the motor casing 22, or wholly within said casing between the field coils 21.

In short, the liquid or semi-liquid wax or other finishing material from within the reservoir, passing through the channel 29 and tube 20, is heated within the tubular sections 26 under the influence of the waste heat generated by the electric current within the field coils 21, due to the continual rapidly changing polarity of the magnetic iron cores and of the casing between and surrounding said field coils. Also, the flow of finishing material as before stated may be manually controlled by the valve 35, or may be automatically regulated by any suitable means such for instance as the centrifugally movable ball valves 45 within the hollow connecting member 11, said ball valves being operative to close the nozzle apertures 46 in said member when the finishing members 10 are stationary, and being operative to shift radially outwardly and thereby to open said apertures as said finishing members commence to rotate.

Referring now to Figs. 5, 6, 7 and 8, the structure here illustrated comprises the motor, surrounding casing, and depending canopy and peripheral skirt, beneath which the finishing members 10 operate. However, instead of a relatively high reservoir above the motor and either within or beside the handle 36, the cylindrical motor casing 22 is provided with integral, laterally extending, projections 50 and 51, preferably in line with upper and lower tangents to said casing, and outwardly connected together by an upwardly extending wall 52, which with end walls 53 and 54, incloses a tank adapted to serve as a reser-

voir for the liquid finishing wax, or other material. The uppermost wall 50 is provided with a filling port, normally closed by a plug 55, having a suitable vent 56, while each of the end walls 53 and 54 is provided with an aperture, connected by a tube 57 with the interior of the casing 58 (see Fig. 8), in which the shafts 59 rotate.

Each of the said shafts 59 has an axial bore 60, communicating through upwardly and diverging bores 61 with a peripheral external groove 62 into which the liquid material flows from the reservoir. Each of said shafts is provided with an anti-friction bearing 63, positioned to one side of the intake tube 57 and with a liquid-tight collar 64, said bearing and collar being operative to minimize the amount of liquid which would otherwise pass by the exterior of each shaft, without entering the bores therein. Each shaft is also provided, as in the previous instance, with a worm gear 17 rotatable within the housing 16, while, however, the upper open end of the housing in this case is closed by means of a suitable plug or cap 65. On the other hand, the lower end of each shaft is provided, as in the previous instance, with a hollow terminal member 11, to which is secured one of the finishing members 10 as hereinbefore described.

One end wall of the reservoir is provided with an aperture 66 through which extends a casing 67, containing an electric heating unit 68 of any suitable construction and the terminal wires 69 and 70 which are connected in parallel with the motor which drives the finishing elements. However, there may be interposed in either of said terminal wires any suitable type of thermostatic electrical control 71, which may be positioned within a surrounding casing 72 which is secured within a second aperture 73 in a wall of said reservoir. With this construction, after the motor has been in operation for a short time, and particularly when alternating current is in use, the waste heat from the motor passes from the casing 22 and both directly into the finishing material within the reservoir and indirectly into said material, after first passing into the upper and lower walls 50 and 51 and the end walls 53 and 54 of said reservoir. It is to be understood that this method of raising the temperature of the liquid or semi-liquid finishing material is sufficient for that purpose in many cases and does not require the heat separately applied through the coil 68, nor the regulation of this supplementary heat by means of a thermostat or otherwise.

In fact, it is probably true that only in relatively large sizes of the device is it necessary to employ the separate heating unit, and it is true that the contents of the reservoir may be heated by means of this unit whether or not the reservoir receives heat also from and as a result of close association with the motor casing and the waste heat generated therein. However, in each case the temperature to which the finishing material is raised to insure the best results upon the surface being treated is determined by properly adjusting the thermostat 71 in well-known manner, so that when the proper temperature is reached the supply of electric current is shut off from the heating unit and is again restored when the temperature of the material decreases below a certain previously fixed point.

Furthermore, where both arrangements for heating the material are combined as shown in Figs. 5, 6, 7 and 8, it is possible to first heat the material within the reservoir by means of the

heater unit 68 and thereafter maintain said temperature by the waste heat from the motor as before described, so that these two methods may be used independently or conjointly as may be desired.

Referring now to Fig. 9, a form of the device is shown in which the vertical section of the shaft 12, brush or the like 10, and surrounding casing is practically the same as that shown in Fig. 3, except that the upper open end of the casing is closed by a plug or cap 65 as is shown in Fig. 8. Also, liquid material from within a superimposed reservoir, such for instance as that previously shown in Fig. 2 as being in the handle of the device, passes by way of a flexible tube 75, through a port 76 in the lower portion of the housing 77 surrounding the worm gears 17 upon the shaft 12. It will be noted that the worm 18 upon the motor shaft 19 also extends into and engages said gear within said housing.

With this structure in mind, it will be seen that the waxy material from the reservoir flowing into said housing surrounds said gear and worm and finally, after being thoroughly churned and mixed to an even consistency by said gears, and raised in temperature by heat from the motor casing 22 with which the walls of the housing 77 are in contact, passes into and downwardly through the bore 13 and into the hollow end member 11, where its flow is automatically controlled by means of the ball valves 45 if desired, and thence passes from the nozzle apertures 46 upon the bristles of the brush or similar finishing member 10.

Thus I have described and illustrated this invention as comprising three methods for heating the wax or other finishing material while in its reservoir or while passing from the reservoir to the nozzles which spray it upon the finishing elements. In each case, however, the waste heat from the motor is employed and in one instance combining therewith a separate source of heat in the form of an electrically energized unit which may be employed independently of, or in conjunction with the motor heat as before described.

Having thus described my invention, what I claim and desire to protect by Letters Patent of the United States is:—

1. In a device of the character described, the combination of a motor, a finishing member actuated by said motor, a motor-supporting frame, a reservoir also carried by said frame, means to heat the contents of said reservoir, a conduit adapted to convey finishing material from said reservoir towards said member, a nozzle, and means to automatically regulate the flow of said material from said nozzle in accordance with the operation of said member.

2. In a device of the character described, the combination of an electric motor having a casing comprising a part of the path of the magnetic field and heated by the variations in current thru the field coils, with a coil of tubing in said casing, and a finishing member actuated by said motor, said coil being adapted to convey finishing material in proximity to, and so as to be heated by, the motor field, whence said material flows towards said member.

3. In a device of the character described, the combination of a motor, a finishing member actuated by said motor, a handle for propelling the device, a reservoir carried by said handle, and a metal conduit leading from said reservoir in proximity to the magnetic flux paths of, and

adapted to be heated by the waste heat from, said motor and towards said member.

4. In a device of the character described, the combination of a motor, a handle for propelling the device, a reservoir within said handle, a coil of tubing within, and heated by the waste heat from said motor, a nozzle, a connection between said reservoir and said coil, and a second connection between said coil and said nozzle. 85

5. In a device of the character described, the combination of a motor, a shaft driven by said motor and having a bore, a finishing member carried by said shaft, a handle to propel the device, a reservoir carried by said handle, a coil of tubing within said motor and adapted to be heated by the waste heat from said motor, a conduit to lead material from said reservoir to said coil, a connection between said coil and the bore in said shaft, and means to control the flow of such material through said conduit. 95

6. In a device of the character described, the combination of a motor, a shaft driven by said motor and having an axial bore, a finishing member carried by said shaft, a handle to propel the device, a reservoir within said handle, a coil of tubing within said motor and adapted to be heated by the waste heat from said motor, a conduit to lead material from said reservoir to said coil, a valve to regulate the flow of material to said coil, a connection between said coil and the bore in said shaft, a nozzle carried by said shaft, and means to automatically regulate the flow of material from said nozzle in accordance with the operation of said member. 105

7. In a device of the character described, the combination of a motor which generates heat within its casing, a reservoir in direct contact with said casing and adapted to be heated by the heat in said motor, a finishing member actuated by said motor, and a channel to lead material from said reservoir through said casing to said member. 115

8. In a device of the character described, the combination of a motor which generates heat and is surrounded by a casing, a reservoir having a single wall in direct physical contact with and adapted to be heated by the heat in said casing, a finishing member actuated by said motor, and a channel to lead material from said reservoir towards said member. 120

9. In a device of the character described, the combination of a motor, a finishing member actuated by said motor, a reservoir having an outlet, a heating unit within and adapted to heat material also within said reservoir, said unit being located near said outlet, and a conduit to lead heated material from said reservoir towards said member. 130

10. In a device of the character described, the combination of a motor, a finishing member actuated by said motor, a reservoir in direct contact with and adapted to receive waste heat from said motor, an electric unit to initially heat material within said reservoir, a thermostat to automatically stop the flow of electric current in said unit, after heat from said unit and from the motor have raised the temperature of such material to a predetermined degree, and a conduit to lead material from said reservoir towards said member. 140

11. In a device of the character described, the combination of a motor having a casing, a finishing member actuated by said motor, a reservoir in direct physical contact with said motor, an elec- 145

- tric unit within and operative to initially heat material also within said reservoir, a thermostat to automatically stop the flow of electric current in said unit, after heat from said unit and from the motor have raised the temperature of such material to a predetermined degree, and a conduit to lead material from said reservoir towards said member. 80
12. In a waxer, a casing having a reservoir chamber therein, a motor within the casing, a waxing unit driven by said motor, and means within the reservoir chamber for heating the wax. 85
13. In a floor waxer, a housing, a motor within the housing, a brush, gearing connecting said motor and said brush, a wax reservoir, means for conveying wax from the reservoir, including one portion within the housing in which portion the wax is heated by waste motor heat after it leaves the reservoir, said portion being of metal and constituting part of a heat conductive path between the motor and the wax in the conduit. 90
14. The device of claim 13 in which the portion of the means lies in close proximity to the field core of the motor to absorb heat generated by the motor. 95
15. In a compact two brush waxer, a frame including a base plate, a motor cage, a reservoir, and two shaft housings; a shaft within each shaft housing, the two shafts having parallel vertical axes in the lateral center line of the base plate and equi-spaced with respect to the fore and aft centerline, a motor in the cage with its axis parallel to said lateral centerline, on the opposite side from the reservoir, means within the frame for operatively connecting the motor and the shafts, waxing brushes on the shafts supporting the waxer, and means within the frame for initially heating the wax, said means becoming inoperative for heating the wax when the heat delivered from the motor thru the frame to the reservoir reaches a chosen amount. 100
16. In a waxer, a motor, a motor casing, a reservoir one wall of which is a wall of the motor casing, a resistance element within the reservoir for initially heating the wax, and a thermostat controlled switch for disconnecting the element when the heat thru the common wall sufficiently heats the wax. 105
17. In an electric motor driven waxing and polishing machine, a reservoir for holding wax for said machine, a brush connected to be driven by the motor, a passageway leading from said reservoir to said brush, part of the metal surface touched by undelivered wax being arranged in close proximity to the magnetic paths of the motor flux whereby part of the heat generated by the motor current is utilized to heat the wax. 110
18. In a floor waxing machine, a brush, a reservoir for holding the wax, a wax carrying passageway between the reservoir and brush, an electric motor for driving the brush, paths for the motor current including the motor windings, part of said paths being so positioned with respect to the wax containing elements that the wax carried by the machine is warmed by heat generated in said paths, whereby a freely flowing fluid is delivered to the brush. 115
19. The device of claim 18 having additional means for warming the wax, comprising an electric heating coil connected in parallel with said motor. 120
20. The device of claim 18 having auxiliary means for warming the wax consisting of a resistance coil connected in parallel with said motor, a thermostat in series with said coil and arranged in heat transfer relation with said wax whereby the auxiliary means is disconnected after the wax attains a certain temperature. 125
21. A machine for applying liquid to a surface, an electric motor for driving said machine and means for heating the liquid, said means comprising part of the paths of the motor flux. 130
22. In an electric motor driven surface finishing machine, a finishing member actuated by the motor, a reservoir for carrying a material to be applied to a surface to be finished, means for carrying the material from the reservoir to the surface, and means for heating said material in proportion to the amount of electric power delivered to said motor. 135
23. The machine of claim 22 in which said means is adapted to heat the material after it leaves the reservoir. 140
24. The machine of claim 22 in which said means is adapted to heat the reservoir. 145
25. In a floor waxer, a housing, a motor within the housing, a brush, gearing connecting said motor and said brush, a wax reservoir, means for conveying wax from the reservoir, including one portion within the housing in which portion the wax is heated by motor generated heat, a portion of said means surrounding a part of the gearing. 150

CLINTON E. WOODS.
